UNITED STATES PATENT OFFICE.

JOSEPH T. ROBIN, OF NEW YORK, N. Y.

DESIGN FOR A PORTABLE SHOW-CASE.

SPECIFICATION forming part of Design No. 35,248, dated October 29, 1901.

Application filed September 27, 1901. Serial No. 76,807. Term of patent 7 years.

To all whom it may concern:

Be it known that I, JOSEPH T. ROBIN, of the borough of Manhattan, city, county, and State of New York, have invented a new and original Design for Portable Show-Cases, of which the following is a specification.

My design consists in a show-case having a substantially horizontal bottom and vertical back, front, and sides, with an inclination of the upper edges of the latter toward the front and a cover resting upon the upper edges of the front, back, and sides, and hence having an inclination toward the front, the said bottom being supported at its corners on legs 5 tapering downwardly lengthwise of the front and back and of the sides.

My design is illustrated in the accompanying drawings, in which—

Figure 1 is a side view of a show-case embodying the design. Fig. 2 is a front view of the same. Fig. 3 is a back view of the same.

A designates the bottom of the show-case, and it is substantially horizontal; B designates the front; C designates the back, and

B¹ B² designate the sides; all being substantially vertical. The sides taper forwardly by reason of an inclination of their upper edges.

D designates a top, constituting a cover, which is hinged at its rear edge to the back of the show-case. By reason of the forward taper of the sides this cover has a forward inclination.

E designates legs arranged at the corners of the bottom of the show-case. They are of ornamental configuration, characterized by a downward taper lengthwise of the edges of the parts of the box to which they are attached.

What I claim is—

The design for a show-case substantially as shown and described.

In testimony whereof I have signed my name to this specification in the presence of two subscribing witnesses.

JOSEPH T. ROBIN.
